UNITED STATES PATENT OFFICE.

ANTHONY VANDERVELD, OF GRAND RAPIDS, MICHIGAN, ASSIGNOR OF ONE-HALF TO
STEPHEN E. PARRISH, OF GRAND RAPIDS, MICHIGAN.

CLOTH OR RIBBON MEASURING MACHINE.

Application filed August 11, 1921. Serial No. 491,323.

To all whom it may concern:

Be it known that I, ANTHONY VANDERVELD, a citizen of the United States of America, residing at Grand Rapids, in the county of Kent and State of Michigan, have invented certain new and useful Improvements in Cloth or Ribbon Measuring Machines; and I do hereby declare the following to be a full, clear, and exact description of the invention, such as will enable others skilled in the art to which it appertains to make and use the same.

This invention relates to cloth or ribbon measuring and cost computing machines of the character shown in my prior application for patent, Ser. No. 440,578, filed Jan. 28, 1921, and patented June 20, 1922, Patent Number 1,420,612.

The present invention has for its primary object and purpose, the provision of means used in connection and combination with the measuring mechanism of the structure for automatically interposing a stop for the entrance of cloth or the like into the machine after it has once been operated through a cycle of operations, until such time as the brake mechanism forming a part of the mechanism has been released to permit the measuring mechanism to return to its initial position, with the indicators at zero position, the stop means used being automatically moved out of the way and to an inoperative position with the release of the brake mechanism. A further object of the invention is to provide a means of this character which is very simple in construction and operation and which does not in any way interfere with the effective operation of the machine other than above stated, this insuring that the beginning of a measuring operation will, at all times, be with the indicator mechanism at its initial zero position.

The construction embodying my invention by means of which the above described ends and many others subsidiary thereto are accomplished is illustrated in the accompanying drawings, in which,

Fig. 1 is a partial side elevation and sectional view vertically through the machine showing the stop member in operative position.

Fig. 2 is a horizontal section substantially on the plane of line 2--2, of Fig. 1.

Fig. 3 is a fragmentary side elevation with

parts broken away and shown in section illustrating the lifting of the stop member to inoperative position.

Fig. 4 is a fragmentary side elevation illustrating the means used for operating the presser roller to inoperative position.

Fig. 5 is a vertical section taken through the front portion of the machine and looking to the rear, and

Fig. 6 is a fragmentary plan view of the front end of the machine.

Like reference characters refer to like parts in the different figures of the drawings.

In the construction of the measuring machine, a base 1 is provided on and above which the mechanism is mounted, the same being enclosed in a covering casing having sides 2 and 3, a back 4, top 5 and partial front side 6 which extends downwardly to within a comparatively short distance from the base. The top 5 has a relatively large rectangular opening therein which is filled with glass or other transparent material 7, while the front 6 has an opening there-through filled with a glass 8.

At the lower front portion of the machine below the lower edges of the front 6 of the casing and adjacent portions of the sides 2 and 3, a table 9, Fig. 5, with depending sides and front 10 is secured, completing the casing for the enclosure of the mechanism, a slot 11 being left for the entrance of the cloth over the table and between the measuring and presser rollers, as will later appear.

The base 1 supports a supporting frame structure for carrying the mechanism of the machine, said frame including side plates 2^a and 3^a, a rear plate 4^a and a front plate 6^a, all spaced from and paralleling the vertical sides 2 and 3, the back 4 and the front 6 of the enclosing casing, as shown.

A measuring roller 12 attached to a shaft 13 mounted between the front and rear frame plates 2^a and 6^a is located directly over the table 9. Shaft 13 carries a pinion 14 which drives a train of gearing, indicated as a whole at 15 (see Fig. 1), with which is associated a shaft 16 driven by the gearing. The size of the roller 12 is such and the design of the gearing between it and the shaft 16 is such that the shaft makes one complete revolution with each yard of goods passed through the machine in contact with the measuring roller. An in-

5 indicator cylinder 17 is fastened to and turns with the shaft 16. A second shaft 18 is also driven by the gearing, around which a spring 19 is wound, fixed at one end but connected with the gearing at the other end, it being obvious that the operation of the measuring roller and associated shafts and 10 gearing described serves to tension the spring and store up energy tending to return the mechanism to initial position when free to do so.

15 The indicating cylinder 17 carries a series of indicating characters indicating fractional parts of the unit of measurement which are successively visible through an opening 20 in a sheet metal plate 21 located directly under the top 5 of the casing as shaft 16 is rotated, thereby indicating the fractional parts of each yard of goods 20 passed through the machine as the same is drawn therethrough.

25 On the front end of shaft 18 a disk 22 is secured from which a plurality of pins 23 project forward, being equally spaced apart and adapted to have engagement with teeth 24, Fig. 5, formed on a central enlargement of an indicating member 25 which is loosely mounted between its ends to turn about a horizontal axis provided by a shaft projecting through and in front of the front frame plate 6^a. This indicating member includes an upwardly extending arm 26 formed at its extreme upper end with a rearwardly turned pointer 27 which is designed to pass 30 over a yards indicator scale formed on the upper side of the arcuate front portion 28 of the plate 21, as best shown in Figs. 5 and 6. In addition, the member includes a downwardly extending arm 29 which, adjacent its lower end is bent forwardly and then again downwardly, as shown at 30, to pass through a slot cut in the lower portion of a plate 31, Fig. 1, positioned vertically in front of the front frame plate 6^a. It will 35 be evident that the indicating member 25 is moved with the rotation of the measuring roller, and the design is such that for each yard of goods passed by the measuring roller the pointer 27 passes from one indicating 40 number of the scale at 28 to the next succeeding higher number, there being provided with the indicating cylinder 17 and the scale at 28 with the pointer 27 moving thereover, a complete indication of the yards 45 and fractional portions of a yard passed through the machine. Of course, this machine has the front indicator also as shown in my pending application for patent, above noted, the lower arm 29 and pointer 30 being a part thereof, but as it is no particular or essential feature of the present invention 50 it is not fully shown and described.

55 The cloth or like goods passed by the measuring roller is pressed into contact therewith by a presser roller 32 (see Fig. 3)

60 mounted on and between the ends of levers 33 connected with a sleeve 34 (see Figs. 4 and 5) which is loosely mounted on a horizontal rod 34^a. A spring 35 around the sleeve 34 bears at one end on the base 1 and 65 connects with the other end of one of the levers 33. This spring exerts a torsional force tending to press the presser roller 32 against the measuring roller 12, or against the cloth placed between the rollers, when 70 free to do so, thereby causing the cloth to frictionally engage the measuring roller so as to turn the same when it is drawn lengthwise through the machine between said measuring and presser rollers. 75

80 Projecting upwardly from the base 1 and cast integral therewith are three vertical supports 36, 36^a and 36^b (see Fig. 2), spaced from each other. A sleeve 37 (see Fig. 2) is rotatably mounted in and extends through support 36 and at its outer end is equipped with an operating lever or handle 38. This lever carries a notching knife, not shown, as the lever and sleeve form no part of the present invention other than as the sleeve 85 forms the housing in which a second sleeve 39 is rotatably mounted, it likewise being equipped with an operating lever 40 at its outer end. This sleeve, at its inner end extends to and is mounted in the support 36^a. 90 Sleeve 39, between the supports 36 and 36^a carries a cam member 41 (see Figs. 2 and 3) formed with a section of reduced radius of curvature and a second section of larger radius of curvature with an inclined shoulder 42 connecting one section to the other over which the forwardly projecting portion 43 of a spring brake member 44 rides when the lever 40 is moved in a downward direction. The brake member 44 is secured at its 95 lower end to the base 1 and at its upper portion is adapted to bear against a member 45 (Figs. 1 to 3) rotatable with the shaft 13, thereby holding the shaft 13 and associated 100 parts of the measuring mechanism against 105 return movement from the action of spring 19 until the brake is released. The shaft 13 is shown screw threaded for a purpose fully explained in my pending application for 110 patent above identified, but which is no part 115 of the present invention and, therefore, not specifically described in this application. As soon as the lever 40 is lifted, the brake is released and the parts are free to return to initial position by spring 19. 120

125 The cam member 41 is formed with a shoulder 46 at the opposite end of the reduced section of the cam where it joins with the section of larger radius. An irregularly shaped stop member 47 is loosely mounted at one end on the sleeve 39, having a pin 48 secured thereto which extends across the cam 41 between the shoulders 42 and 46. The stop member 47 extends forwardly nearly to the front of the machine and terminates at 130

its end in an arm 49 which is adapted to drop on to the table 9 and into a slot 50 (see Fig. 5) cut in the upper side thereof when free to do so, thereby interposing a 5 positive stop against the entrance of cloth or like goods between the measuring and presser rollers when this stop is down. Normally the stop member 47 is elevated to the 10 position shown in Fig. 3, due to the engagement of shoulder 46 of the cam 41 with the pin 48, this occurring when the lever 40 is raised to its normal position when the machine is ready for operation. When thus elevated, the arm 49 at the front end of the 15 stop member is carried into a slot 51 cut in the plate 6^a for the purpose of receiving the arm in its upper position. In such upper position, the entrance opening or slot 11 in the casing is free and unobstructed and cloth 20 or the like may be entered therein.

A rod 52 extends through sleeve 39 and through supports 36^a and 36^b, it at its outer end having an operating handle or lever 53 attached. At its inner end between the supports 36^a and 36^b, a cam 54 (see Figs. 2 and 4) is secured which is adapted to actuate a 25 lever 55 pivotally mounted between its ends, one end bearing against the cam and the other passing under the free end of the lever 30 33. (See Figs. 2, 4 and 5). When lever 53 is moved to lower position, cam 54 rides over the end of the lever 55 and serves to thereby move the presser roller 32 away from the measuring roller and hold the same away 35 until lever 53 is moved again to upper position.

In the operation of the machine, it being at initial position and with the indicator mechanism at zero position, and with the 40 presser roller moved away from the measuring roller, brake 44 being free from engagement with the member 45, cloth or the like may be introduced between the rollers, whereupon the lever 53 is raised and the 45 presser roller brought against the cloth to press it against the measuring roller, as in Fig. 3. The cloth may then be drawn through the machine actuating the measuring roller and connected mechanism, the indicator mechanism showing the amount of 50 cloth or like goods passed. When the required amount has been measured, all of the levers 38, 40 and 53 are depressed, the cloth being notched, brake 44 set against member 55 45 and the presser roller moved to lower position. The brake holds the measuring and indicator mechanism against return. At the same time, the operation of setting the brake has moved cam 41 so as to permit the stop member 47 to fall by gravity against the upper side of the cloth, indicated at C. The cloth may now be freely drawn from the machine and the required amount cut off at the notch made, the stop member seating in the 60 groove or slot 50 in table, and blocking the 65

entrance of cloth between the rollers until such stop member is lifted. This is done by raising lever 40 so that cam shoulder 46 engages pin 48 as previously described. Simultaneously the brake 44 is released, and spring 19 returns the measuring mechanism to initial position with the indicators at zero, the rollers being left apart for the entrance of cloth for the succeeding measuring operation.

It will be apparent that the brake setting and stop dropping operation is entirely independent of the operation for separating the measuring and presser rollers. Each is done independently by an independent 80 mechanism. The operation of the stop member to either operative or inoperative position is intimately connected with the brake setting and release, and has no connection with the presser roller operation. 85 The advantages of the stop member are self evident. The machine must be set at zero at the beginning of every measuring operation and there can be no likelihood of having the indicators show the sums of two 90 or more lengths of goods measured, as the stop bar absolutely prevents introduction of goods when the indicators show other than zero, due to the fact that the brake mechanism must be released in order to elevate the stop member to upper inoperative position, and such release of the brake immediately frees the mechanism so that it will return so that the indicator mechanism indicates zero position.

The appended claims define the invention, and I consider the invention to include all constructions coming within their scope.

I claim:

1. In a machine for measuring cloth or like material, the combination with a measurement indicator, measuring mechanism for operating the same, including movable members for engaging the material to be measured, means for releasing engagement between said members and the material at the end of a measuring operation, means for returning the indicator to zero position, means independent of the means for releasing engagement between said members and said material for stopping and holding the measuring mechanism and indicator operated thereby in fixed position at the end of a measuring operation, said last mentioned means being operable to release the measuring mechanism to return to initial position and the indicator to return to zero position, and means automatically released by the setting of said stopping and holding means for preventing entrance of material between the said movable members, substantially as described.

2. In a machine for measuring cloth or like material, the combination with a measurement indicator, measuring mechanism

75

130

for operating the same by the passage of said material therethrough, means for returning the measuring mechanism and indicator to initial zero position, brake means for holding the measuring mechanism and indicator in fixed position at the end of a measuring operation, and means automatically released by the setting of said brake means for preventing entrance of material into the machine until the brake means is released, substantially as described.

3. In a machine for measuring cloth or like material, measuring mechanism adapted to be operated by drawing said material therethrough, a measurement indicator operated by the said mechanism, means tending to normally return the mechanism and indicator to initial zero position, means for holding said mechanism and indicator against return at the end of a measuring operation, means for operating said holding means, and means likewise operated by said operating means for automatically interposing a stop against the introduction of material into the machine when the holding means is set, and moving said stop out of the way when said holding means is released.

4. In a machine for measuring cloth or like material, measuring mechanism including a measurement indicator operated by drawing the material lengthwise through the machine, means normally tending to return the mechanism and indicator to initial zero position, means for holding said mechanism and indicator against return, means for manually operating said holding means to operative or inoperative positions, and means connected with and operated by said manually operated means for interposing a stop against the entrance of material into the machine during the time the holding means is in operative position, but permitting free entrance of the material into the machine when the holding means is in inoperative position.

5. In a machine for measuring cloth or like material, measuring mechanism including a measuring and a presser roller, means normally tending to press the presser roller against the measuring roller, means for moving the presser roller away from the measuring roller and hold it away therefrom, a measurement indicator operated by the measuring mechanism, means normally tending to return the measuring mechanism and indicator to initial zero position, manually operable means for holding the same against return, and stop means operable with said holding means for preventing the entrance of material between the rollers while the holding means is in operative position, but permitting free entrance of the material between the rollers when the holding means is released to inoperative position.

6. In a machine for measuring cloth or

like material, measuring mechanism including a measurement indicator operable by drawing the material lengthwise therethrough, means controlled by the operator of the machine for returning the mechanism and indicator to initial zero position, and means automatically operated by the operator of the machine when controlling said return means for providing a stop against the entrance of material into the machine except when the machine is at initial zero position, substantially as described.

7. In a machine for measuring cloth or like material, a measuring and a presser roller between which the material is drawn, measuring mechanism including a measurement indicator driven by the measuring roller, manually operable brake means for holding the measuring roller and associated mechanism in any position to which operated, spring means tending to return said measuring roller and associated mechanism to initial zero position, and a stop member associated with the manually operable brake means and controlled by the operation thereof to interpose against the entrance of material between the rollers when the mechanism is at other than initial zero position.

8. In a machine for measuring cloth or like material, a measuring and a presser roller between which the material is drawn, measurement mechanism including a measurement indicator driven by the measuring roller, a shaft, a cam on the shaft, means for manually operating the shaft, a brake actuated by movement of the cam to hold the measuring roller and associated mechanism in any position to which moved, means normally tending to return the said mechanism and indicator to initial zero position, a stop member mounted adjacent the shaft, and interengaging means between the cam and said stop member for moving the stop member to inoperative position when the brake is inoperative, said member moving by gravity to operative position to stop entrance of material between the rollers when the brake is set, substantially as described.

9. In a machine for measuring cloth or like material, a measuring and a presser roller between which the material measured is drawn lengthwise, measuring mechanism including a measurement indicator driven by the measuring roller, spring means tending to return the same to initial zero position, a brake adapted to stop the said mechanism and indicator and hold the same against movement at the end of a measuring operation, a cam for actuating said brake, manually operable means for operating the cam, a stop member movably mounted adjacent the cam and extending forward alongside the measuring roller, said member normally dropping by gravity when free to do so to thereby prevent entrance of mate-

- rial to be measured between the rollers, and interengaging means between the cam and said stop member whereby movement of the cam when the brake is released lifts the stop member to an inoperative position, and movement of the cam in the opposite direction when the brake is set frees the stop member to drop to stepping operative position.
- 10 10. A measuring mechanism for measuring cloth or like material drawn therethrough, including a measurement indicator, spring means normally tending to hold the mechanism and indicator at initial zero position, said means being overcome and energized by operation of the mechanism, a brake for holding the mechanism and indicator to any position to which operated at the end of a measuring operation, manually operable means for setting and releasing said brake, and stop means controlled by said manually operable means for preventing entrance of cloth or like material into the machine for measurement except when the mechanism and indicator are at initial zero position.

In testimony whereof I affix my signature.

ANTHONY VANDERVELD.
